(57) **CLAIM**

The ornamental design for an apparatus for recharging batteries, as shown and described.

DESCRIPTION

FIG. 1 is a perspective view of an apparatus for recharging batteries in accordance with my new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof; and,

FIG. 7 is a left side elevation view thereof.

The broken lines in the figures are for the purpose of illustrating the unclaimed portions of the apparatus for recharging batteries and form no part of the claimed design.
